UNITED STATES PATENT OFFICE

WILLIAM J. NOBLE, OF NEW YORK, N. Y.

DESIGN FOR A COFFIN.

SPECIFICATION forming part of Design No. 14,475, dated December 11, 1883.

Application filed August 11, 1883. Term of patent 7 years.

To all whom it may concern:

Be it known that I, WILLIAM J. NOBLE, of the city, county, and State of New York, have invented a new and original Design for Caskets, of which the following is a full, clear, and exact description.

The nature of my design is fully shown in the accompanying drawings, in which Figure 1 represents a side view of my improved casket, and Fig. 2 an end view of the same.

Similar letters of reference indicate corresponding parts.

The design relates to funeral-caskets; and it consists of the shape and configuration of a casket-body having an inwardly-curved symmetrical base, an outwardly-swelling main portion of ogee shape, and a top conforming approximately to the base, as will hereinafter appear.

20 A in the drawings represents an inwardly-curved symmetrical base, and B the main portion of the casket-body, which main portion is of outwardly-swelling ogee shape.

25 C is an inwardly-curved symmetrical top, which conforms approximately to the base.

The ends of the casket may be round or octagonal, the configuration of the casket body being the same in both cases.

Having thus described my design, I claim as new and desire to secure by Letters Patent—

1. The design for a funeral-casket, composed of a casket-body having an inwardly-curved symmetrical base, outwardly-swelling main portion of ogee shape, and an inwardly-curved symmetrical top, substantially as shown and described. 35

2. The design for the body of a casket, composed of a molded base and a main part of inverted-ogee shape extending upward from the base, substantially as shown and described. 40

In testimony that I claim the foregoing as my invention I have signed it this 9th day of August, 1883.

WILLIAM J. NOBLE.
